UNITED STATES PATENT OFFICE.

JOHN WEBSTER, OF EAST PROVIDENCE, RHODE ISLAND.

DESIGN FOR A HAIR-BRUSH.

41,768.

Specification for Design.

Patented Sept. 12, 1911.

Application filed April 21, 1910. Serial No. 556,903. Term of patent 14 years.

To all whom it may concern:

Be it known that I, JOHN WEBSTER, a citizen of the United States, residing at East Providence, in the county of Providence and State of Rhode Island, have invented a new, original, and ornamental Design for Hair-Brushes, of which the following is a specification, reference being had to the accompanying drawing, forming part thereof, in which—

tive view of the same; and Fig. 3 is a plan view thereof.

The design consists solely in the shape of the brush as an entirety.

I claim—

The ornamental design for a hair brush substantially as shown and described.

JOHN WEBSTER.
